UNITED STATES PATENT OFFICE.

THOMAS DUNCAN, OF CHICAGO, ILLINOIS, ASSIGNOR TO THE SIEMENS & HALSKE ELECTRIC COMPANY OF AMERICA, OF CHICAGO, ILLINOIS, A CORPORATION OF ILLINOIS.

ELECTRIC METER.

SPECIFICATION forming part of Letters Patent No. 698,651, dated April 29, 1902.

Application filed August 21, 1899. Renewed October 2, 1901. Serial No. 77,300. (No model.)

To all whom it may concern:

Be it known that I, THOMAS DUNCAN, of Chicago, in the county of Cook and State of Illinois, have invented certain new and useful

5 Improvements in Electric Meters, (Case No. 59,) of which the following is a specification.

This invention relates to improvements in alternating-current electric meters or measuring instruments for use on circuits carrying heavy currents and in which series transformers are employed to reduce or transform the heavy current down to one of moderate or minute volume before subjecting the delicate mechanism of the meter to its influence. My 10 previous application, filed May 24, 1899, Serial No. 718,023, (Case No. 56,) sets forth a method of correcting the inaccuracy of the ordinary series transformer as employed in this connection by connecting the secondary 15 circuit of the transformer in shunt around its primary and placing the series field-coil of the meter in series with this secondary shunt-circuit. The present invention attains the same accuracy in results by connecting the 20 series field-coil of the instrument in a circuit which is shunted around the primary of the transformer, but is connected in parallel with the secondary circuit thereof, as will be fully understood from the following detailed 25 description of the construction illustrated in the 30 accompanying drawings, in which—

Figure 1 is a somewhat diagrammatic view of a commutating wattmeter designed and connected in accordance with the present improvements. Fig. 2 is a still more diagrammatic view showing an adjustable resistance in the secondary circuit and means for varying the number of turns thereof. Fig. 3 shows a similar construction in indicating- 35 wattmeters. Fig. 4 shows an induction motor-meter constructed and connected in accordance with these improvements.

In the drawings, Fig. 1, A and A' designate the main leads of the work-circuit, B the alternating-current generator, to the brushes of which the leads are connected, and C the magnetic core of a series transformer the primary coil A² of which is connected in series in the main lead A.

50 D designates the series field-coils of an or-

dinary commutating meter, and d d' the leads of a shunt-circuit leading around the primary a of the transformer and in which the coils D are connected.

E designates a secondary coil wound on the 55 transformer-core C and connected with the terminals d² d³ of the shunt-circuit d d', so that it is in parallel with the circuit d d' and with the series field-coil D of the meter. By properly proportioning the number of turns 60 and resistance of this secondary coil E with respect to the primary A² and field-coils D² of the meter I have discovered that the current diverted through the latter may be maintained at all times exactly proportional to the 65 current in the main or work circuit, and a meter thus arranged and connected will therefore register as accurately as though its series coils were directly inserted in the main line. 70

Obviously this improvement may be employed with advantage in either ammeters or wattmeters. The instrument shown in Fig. 1, however, is of the latter type and is provided with armature-coils F, which are connected through a commutator F' in a shunt-circuit f f', extending across the line between the main leads A A', a resistance f² of suitable proportions being also provided in this shunt-circuit. A disk F³ is secured upon the 80 spindle F³ of the meter to rotate between drag-magnets G and retard the armature in a manner well understood. The rotations of the latter are then registered by any suitable mechanism R, operatively connected with the 85 spindle. 75

In the construction shown in Fig. 2 the same arrangement of the series field-coils D with relation to the secondary circuit E of the transformer obtains. Means of adjustment, 90 however, are in this case provided in the form of a switch E', by means of which more or less of the turns of the coil E may be cut out, and in an adjustable resistance E², which is also inserted in said secondary circuit. 95

Fig. 3 shows my improvements as embodied in an indicating-wattmeter, and Fig. 4 in an indicating-wattmeter of the induction-motor type. In the former case the adjustable resistance E² is depended on for adjust- 100

ment, while in the latter the switch or adjustable cut-out E' is alone employed. The essential improvement in both cases is, however, the same as heretofore described, and it will be understood that various other applications of the invention may be made without involving any departure from the broad principle which underlies it.

I claim as my invention—

10 1. The combination with a main circuit, of a transformer having its primary coil connected in series in said main circuit and its secondary coil connected in shunt to its primary coil, and an energizing-coil also connected in shunt to the primary coil and in parallel with the secondary circuit.

15 2. The combination with a series transformer having its secondary connected in shunt to its primary circuit, of a measuring instrument or meter provided with an energizing-coil connected in shunt to the primary circuit and in parallel with the secondary circuit.

20 3. The combination with the main circuit, of a transformer having its primary coil connected in series with the main circuit, and its secondary coil connected in shunt to its primary coil, an energizing-coil also connected in shunt to the primary coil and in parallel

with the secondary coil, and means for adjustably varying the relative proportions of the shunt-circuit. 30

4. The combination with a series transformer having its secondary connected in shunt to its primary circuit, of a measuring instrument or meter provided with an energizing-coil also connected in shunt to the primary circuit and in parallel with the secondary circuit, and means for adjustably varying the number of turns in the secondary coil 40 of the transformer.

5. The combination with a series transformer having its secondary connected in shunt to its primary circuit, of a measuring instrument or meter provided with an energizing-coil also connected in shunt to the primary circuit of the transformer and in parallel with the secondary circuit, and means for adjustably varying the resistance of said secondary circuit. 45

In testimony that I claim the foregoing as my invention I affix my signature, in presence of two subscribing witnesses, this 16th day of August, A. D. 1899.

THOMAS DUNCAN.
